COVERALLS

Sid Lawson, New City, N.Y., assignor to Sun Oil Company, Philadelphia, Pa., a corporation of New Jersey

Original design application Sept. 17, 1968, Ser. No. 13,566. Divided and this application Mar. 19, 1970, Ser. No. 21,970

Term of patent 14 years

Int. Cl. D2—01

U.S. Cl. D2—29

FIG. 1.

FIG. 2.

FIG. 1 is a front elevational view of a coverall showing my new design; and

FIG. 2 is a side elevational view thereof, the portion of the back not shown being conventional and plain.

The characteristic feature of my design resides in a combination on the coverall disclosed of a plain, fly front, flanked on each side by a wide and a narrow diagonal stripe extending from the edge of the fly to the middle of the sleeve, substantially as shown.

This is a division of my copending application D. 13,566 filed Sept. 17, 1968.

I claim:

The ornamental design for coveralls, as shown and described.
